UNITED STATES PATENT OFFICE

2,235,092

DUPLICATING MACHINE

Edmund Leo Wall, Detroit, Mich., assignor to The
Cincinnati Milling Machine Company, a corpo-
ration of Ohio

Application September 16, 1938, Serial No. 230,312

26 Claims. (Cl. 90—13.5)

This invention relates to improvements in duplicating machines, its fundamental purpose being to provide a two-purpose machine, the respective purposes being that of a die-sinking machine and that of a milling machine. In considering the general aspects of the instant invention reference may be made to the following patents of Edmund L. Wall; Universal die-sinking attachment for horizontal milling machines, Patent 1,997,891 of April 16, 1935, Duplicating machine, Patent 2,007,231 of July 9, 1935, Automatic carriage control for duplicating machines, Patent 2,007,232 of July 9, 1935, and Universal die-sinking attachment for vertical milling machines, Patent 2,051,430, of Aug. 18, 1938. As already suggested, it is the underlying purpose of the invention to place at the disposal of a machine-shop operator, a machine which is capable of doing either straight milling in the vertical or horizontal directions, or die-sinking.

A machine primarily built to do die-sinking is ordinarily very expensive, the excessive cost prohibiting many machine-shop operators from installing them. Such operators, however, are necessarily equipped with straight milling machines and, generally, separate machines for horizontal and vertical milling are required. It stands to reason that with equipment such as this the shop operator is restricted in the nature of the work which he can turn out.

If it were possible for him to do die-sinking he would have open to him an avenue to a greater income, but, as has been pointed out already, such an avenue is closed to small machine shop operators, because of the high cost of a die-sinking machine.

The instant machine is so arranged that the shop operator can do any kind of vertical or horizontal straight milling which the ordinary machines of these types are equipped to do, but at the same time the instant machine is convertible in its nature, the conversion enabling it to perform a wide variety of die-sinking operations. Thus the small machine shop operator, and others who need not and cannot be classed as small, has at his disposal a two-purpose machine which is extremely flexible as regards the kinds of work which it is adapted to do; further, a machine which can be manufactured and sold at a cost approximately the same as that of a single milling machine of either type, and at a cost so far below that of a die-sinking machine that a comparison at this place would not serve as any useful purpose.

The important acts of the improved duplicat-

ing machine are performed semi-automatically. Most of the work is done by an automatic control, but in every instance a manual act is required, this carrying with it the advantage of constant supervision. With the foregoing statements in mind the objects of the invention are as follow:

First, to provide a two-purpose machine capable of being devoted solely to vertical or horizontal straight milling or to die-sinking, and when the machine is adapted to do die-sinking it has provision for either reproducing surface or perimetric contours.

Second, to embrace the units responsible for the foregoing acts in a hydraulic pressure system which is manually controlled by a three-way valve in changing over from surface contour tracing to perimetric tracing, and vice versa, each function involving the automatic control afforded by a tracer respectively in following surface contours of the master, and top and bottom perimetric contours of the master, the former function further involving a reversing valve which automatically causes the cutter to repeatedly travel up and down periodically reversing the direction of motion until the machine is stopped.

Third, to provide an unusually stable support for the saddle casting which carries the cutter, said support involving the use of screw threads on the vertical plunger shaft on which said casting is rested when the respective plunger is let down to the bottom of the vertical cylinder, thus avoiding any deviation whatsoever of the cutter from its work when used in milling, especially horizontal straight milling.

Fourth, to suspend the saddle casting indirectly from one end of a counter-weighted cable, the interposition of a screw shaft and nut making it possible to anchor, so to speak, the cutter to the immediate cutting point at the work without the necessity of locking a gib for the same purpose, in other words, holding the cutter down to its work with the entire dead weight of the saddle casting, thereby involving the highly improbable circumstance of the cutter ever lifting the saddle casting because of its having encountered a hard spot in the work, resulting in the utmost stabilization of the cutter and making the tracer only responsible for its deviations from the cutting point in most of the performances of the machine.

Fifth, to provide a lead screw, in other words the screw shaft mentioned before, which is reciprocable in the direction of its axis within fixed limits and to adjustably mount the saddle and head castings carrying the cutter and tracer thereon, thereby enabling locating said castings

for work in any region within said limits for a full stroke operation.

- 6 Sixth, to rest the entire saddle casting and its carried parts (the tracer and cutter assemblages) upon the nut of the vertical lead screw, but at the same time to counter-weight said saddle casting and its carried parts so that the operator can maneuver said casting with the utmost ease while profiling either a plaster-cast or a cam model.
- 10 Seventh, to provide a tracer which accomplishes its universal motion in an improved way upon the patent of E. L. Wall for Universal tracer, No. 1,997,890, April 16, 1935.

15 Eighth, to provide a tracer having a barrel or piston valve which is so arranged as to prevent the escape of exhaust fluid under direct force of incoming high pressure fluid, the driving out of the exhaust fluid being accomplished by the admission of high pressure fluid into the opposite 20 end of the respective cylinder, this provision preventing any sudden jumpy movement of the cutter and tracer, particularly in the event when the fluid contains a small amount of air.

25 Other objects and advantages will appear in the following specification, reference being had to the accompanying drawings, in which:

Figure 1 is a front elevation of the improved duplicating machine.

30 Figure 2 is a detail sectional view of the plunger stuffing box of the vertical cylinder.

Figure 3 is a side elevation of the improved machine, a part being shown in section.

Figure 4 is a plan view.

Figure 5 is an end elevation of the head casting.

35 Figure 6 is a central vertical section taken substantially on the line 6—6 of Figure 3.

Figure 7 is a detail sectional view of the quill adjustment taken on the line 7—7 of Figure 6.

40 Figure 8 is a detail sectional view of the quill lock taken on the line 8—8 of Figure 6.

Figure 9 is a horizontal section taken on the line 9—9 of Fig. 1, particularly showing the reversing valve and the pressure fluid passages, for which purpose the column casting is shown partially in section.

45 Figure 10 is a cross section of the reversing valve taken on the line 10—10 of Fig. 9.

Figure 11 is a detail view of the reversing lever, parts being shown in section.

50 Figure 12 is a horizontal section of the reversing valve taken on the line 12—12 of Fig. 1.

Figure 13 is a horizontal section of the previously mentioned three-way valve, taken on the line 13—13 of Fig. 1.

55 Figure 14 is a detail front elevation of the column casting (Fig. 6), illustrating the arrangement of pressure fluid passages.

Figure 15 is a detail plan view of the saddle casting (Fig. 6), the plunger screw being shown 60 in section.

Figure 23 is a cross section of the auxiliary reversing valve taken on the line 23—23 of Fig. 4.

Figure 24 is an end elevation of said valves.

Figure 25 is a cross section similar to Fig. 23 illustrating the shifted position of the valve plug. 5

Figure 26 is a detail cross section taken on the line 26—26 of Fig. 23.

In carrying out the invention provision is made of a base, generally designated 1 (Fig. 1). This base is hollow and contains parts of the operating mechanism as indicated by the dotted lines in Figures 1 and 3. The base has several prominent upstanding parts, one of these designated 2 being herein known as the bed casting, the other one 3 comprising the master and work support. These parts, because of their upstanding relationship to the base define a recess 4 which provides a convenient receptacle for the cuttings from the work.

A trough 5 is attached to the base 1, for example, by casting it integrally therewith, which trough extends around three sides of the base not only to catch oil and metal cuttings but also to provide a convenient ledge for temporarily supporting some of the workman's tools. A plurality of slideways 6 in the top face of the support 3 provide for the affixation of a master and work foundation 7, to which the master or model 8 is suitably secured at 9, and also to which the work 10 is secured at 11. It will be understood that the purpose of the machine when operated as a 30 duplicator is to cause the tracer to "feel" either the surface of the master 8 or the top and bottom of a master so as to reproduce its contours in the work 10 by controlling the cutter accordingly.

With reference to the master 8 it will be perceived in Fig. 1 that its contour is reproduced in the work 10 by periodic up and down movements of the tracer and cutter assemblages. Provision is also made in the machine for contouring the 40 master 8 horizontally because the tracer is as readily responsive to deviations in contour above and below a straight horizontal line as it is to deviations above and below a straight vertical line.

45 The bed casting 2 has parallel flanges 12 (Fig. 6), beneath which the retainer bars 13 of a column casting 14 engage. These bars are attached to the flanges 15 which depend from the casting 14 and ride beside the flanges 12. The casting 50 14 is slidable on the casting 2 for the purpose of shifting the column casting 14 and all of the mechanism that is supported upon it, back and forth in the horizontal direction.

This particular function is obtained by manual 55 means in this particular construction. The column casting 14 has a heavy depending lug 16 (Figs. 3 and 6). A screw shaft 17 is suitably journaled at 18, 19 at its ends upon the bed casting 2 (Fig. 4), the screwed portion 20 of which 60 is in engagement with the threaded bore of the lug 16. A hand wheel 21 on the forward end of the screw shaft 17 has a crank for convenient turning. When the screw shaft is thus turned, the column casting 14 is slid back and forth in the manner already stated.

A column 22 (Fig. 9) is in rigid upstanding relationship to the casting 14, being integral therewith, and perpendicular thereto. This column is necessarily very strong in order to resist any noticeable flexure due to the action of the cutter on the work 10. The fact that the column 22 is hollow (Fig. 9) and that the length of its cross sectional oblong shape stands at right 75

angles to the work is a large contribution to the desired strength of the column.

The space 23 which the hollow column affords provides a passageway for a counter-balancing weight 24 (Figs. 3 and 4). The weight fits the column closely enough to utilize the latter as a guide. The column 22 has a pair of vertical heads 25, 26 (Figs. 4 and 9) which are connected thereto by webs 27. These are narrower than the heads, providing vertical recesses 28. The respective heads 25, 26 have pairs of pressure fluid bores 29, 30 and 31, 32 (Fig. 9). These bores run full length of the heads (Fig. 1). At their upper ends the bores 29 to 32 are appropriately coupled to hoses 33, 34, 35 and 36.

But the hoses 35, 36 are joined directly to the ports 35a, 36a of an auxiliary reversing valve 37a, said ports registering with the bores 31, 32 (Fig. 23). The auxiliary reversing valve is solely for the purpose of causing the tracer head to bear down on the top edge of the master during perimetric tracing as is described in the operation.

A valve plug 38a is subject to a quarter turn in the bore 39a. The turning is done by a handle 40a, and the limiting of the turn is accomplished by a pin 41a, the point of which extends into a segmental slot 42a in the valve plug (Fig. 26). The pin is carried by a cap 43a which 30 provides a closure for the bore 39a.

A pair of diametric passages 44a, 45a (Fig. 23) is intended to provide normal communication of the hoses 35, 36 with the bores 31, 32. At this time the handle 40a points upwards (full lines Fig. 24) and the passages 44a, 45a are in registration with the ports 35a, 36a.

Spiral passages 46a, 47a in the valve plug 38a provide for a reversal or crossing over of the fluid flow in respect to the hoses 35, 36 and bores 31, 32. The terminals of the spiral passages are spaced 90 degrees from the terminals of the passages 44a, 45a. In other words, the terminals of the spiral passages stand half-way between the terminals of the diametric passages. 45 When the valve plug 38a is given a 90 degree turn by moving the handle 40a from the full line to the dotted line position in Fig. 24, the passages 44a, 45a, are disconnected from the ports 35a, 36a, and the spiral passages 46a, 47a 50 are connected thereto (Fig. 25) so that fluid flowing in any one of the hoses is shunted over to the opposite bore in the head 26.

The bores 29, 30 (Fig. 9), respectively, conduct exhaust and high pressure fluid from and to the tracer assemblage (Fig. 18). The bores 31, 32 alternately conduct exhaust and high pressure fluid from and to the vertical cylinder through the tracer assemblage by way of the three-way valve 37.

60 It is preferred to defer the description of the tracer 38 to a later period, but the following parts of the assemblage are described because the routing of the fluid carried by the hoses 33, 34 should be understood. A block 39 has a sleeve 40 fixed in a bore 41. The sleeve is set in the bore very tightly. This sleeve has a series of annular passages 42, 43, 44, 45 and 46 (Figs. 18 and 20). These passages are sunk below the surface of the cylindrical bore 47 of the sleeve 40. Said bore 47 comprises the slide for a barrel valve 48.

Of the foregoing annular passages 42 to 46 (Fig. 20) the central passage 44 always contains high pressure fluid, the passages 43, 45, 75 respectively, at the left and right alternately

containing high pressure and exhaust fluid and the remote passages 42, 46 always containing exhaust fluid. A by-pass 49 joins the exhaust passages 42 and 46. This by-pass is joined by a bore 50 which branches diagonally therefrom 5 to an inlet 51 in the annular concavity 52 of the sleeve 40.

The barrel valve 48 is intentionally seated rather loosely on the surface of the bore 47. This is necessary in order to prevent said valve 10 from sticking. The consequence of this loose mounting is a leakage of fluid into the concavity 52. This is continuously drawn out through the bore 50.

A suitable arrangement of bolts 53 (Fig. 13) 15 secures the casing 37 of the three-way valve to the block 39. The latter has ducts 54, 55, 56 and 57 (Fig. 19), the upper terminals of which communicate in the order named with the exhaust by-pass 49, the high pressure passage 44, 20 the passage 43 and the passage 45. The rear terminals of these ducts open upon the rear face of the block 39 (Fig. 18) where they have communication with the exhaust and high pressure hoses 33, 34, and with the ports in the three-way 25 valve casing.

Said casing has a downwardly directed port 58 which establishes permanent communication between the duct 56 and the bore 59 in the casing. A port 60 is situated diagonally in the 30 casing 37 establishing permanent communication between the duct 57 and the bore 59. The inner terminals of these ports are on a horizontal line where they enter the bore 59. Their outer terminals are on a vertical line because of their 35 having to communicate with the super-imposed outlets of the ducts 56, 57.

The similarly superimposed outlets of the ducts 54, 55, comprise the connecting places of the exhaust hoses 33, 34, from which the previous 40 statement will be understood that the central passage 44 always contains fluid at high pressure whereas there is always a tendency to evacuate fluid from the passages 42, 46, and inlet 51.

Reverting to the three-way valve casing 37, 45 an upright pair of ports 61, 62 provide the places for connection of the inner ends of the hoses 35, 36 (Fig. 4) the far ends of which connect with the bores 31, 32 in the head 26 (Fig. 9). A horizontal pair of ports 63, 64 provide the places of connection of hoses 65, 66, (Fig. 4), the respective ones of which are connected to ports 67, 68 at the left and right ends of a horizontal cylinder 69. It is observed in Fig. 6 that the port 68 has an extension bore in the wall of the cylinder 69, 55 it being the outlet of the latter that has communication with the right end of the cylinder. There is a turnable plug 70 in the bore 59 (Figs. 13 and 18). This plug has a stem 71 which extends through a gland 72 and has a handle 73 60 on its exposed end. The plug has a pair of kerfs 74, 75 (Fig. 13) respectively in vertical line with the ports 63, 61, and with the ports 64, 62. When the handle 73 is set in the horizontal position (Figs. 1 and 18) the kerfs 74, 75 establish fluid 65 communication between the sleeve 40 and the horizontal cylinder 69. At this time the ports 61, 62 are cut off from fluid communication with the sleeve 40.

Tracing the route of the fluid subject to transmission through the hoses 35 and 36 (Fig. 4) which begin at the ports 61, 62 (Fig. 13), the bores 31, 32 to which said hoses are connected at the head 26 (Fig. 9), respectively, join ducts 76, 77 which communicate with the respective top 75

and bottom of a vertical cylinder 78. The head 79 of this cylinder (Figs. 1 and 6) is directly beneath the column casting 14. It is secured thereto by any suitable means. Consequently the 5 vertical cylinder 78 depends from the column casting 14, and is movable back and forth as said column is horizontally slid on its ways 12.

As the result of this dependency of the vertical cylinder it is possible to make direct fluid communication between the top of the cylinder and the duct 76, which like other ducts of its kind (Figs. 9 and 14) are bored in the required directions in the casting 14. The duct 77, however, 10 has to be connected with the bottom of the cylinder 78 by a pipe 80. This is a common pipe, functioning for the conduction of fluid when directed to the vertical cylinder either by the three-way valve 81 or by the reversing valve 81.

This reversing valve comprises the casing 20 noted by the numeral 81 (Fig. 10) which is bolted down at 82 to the column casting 14 (Figs. 6 and 9). The casing 81 has a bore 83 in which a hardened bushing 84 is permanently fixed. The bore 85 of this bushing turnably contains the 25 valve plug 86. This plug has a washer 87 attached to one end of it (Fig. 12). This washer overlaps the bushing 84. The valve plug continues as a stem 88, said stem projecting through a gland 89 in the bushing.

30 The exposed end of the stem 88 turnably carries the hub 90 of a weighted lever 91. This hub is perfectly loose upon the stem 88 so that the lever is free to turn to either side of the vertical dead center, thereby to shift the valve 35 plug into either of its two positions. In order to bring this about the stem 88 has a radially projected pin 92 (Fig. 11) which occupies a slot 93 in the hub. An ear 94 on one side of the hub 90 has a rod 95 connected to it. This rod rides in 40 a guide 96 on the saddle casting and it carries an adjustable pair of stops 97, 98.

A key 87a on the washer 87 fits in a slot 88a in the inner end of the plug 86 (Figs. 12 and 22). This insures the securement of the washer 87 to 45 the valve plug. Said washer has a segmental slot 89a (Fig. 22) into which the end of a pin 90a rigidly carried by a closure 91a projects (Fig. 12). The pin and slot limit the oscillation of the plug 86. The latter can be locked in a central or neutral position by turning a thumb screw 92a inwardly until its end rests in a depression 93a in the washer 87.

The housing 84 (Fig. 10) has four circumferentially spaced ports 99, 100, 101, and 102. 55 These ports communicate with the bore 85 as shown. The plug 86 has a pair of kerfs 103, 104, which are registrable with pairs of said ports in alternation according to the shifting of the lever 91. The casing 81 has passages 105, 106, 107 and 60 108 (Fig. 10), the inner ends of which are in permanent registration with the ports 99, 102.

These passages are directed downwardly. The 65 passage 105 has direct communication with a duct 106, the other end of which joins the bore 30 in the head 25. High pressure fluid is supplied to the duct 109 by a feeder 110 to the nether side of which a high pressure hose 111 (Fig. 6) is coupled at 112 (Fig. 9). The passage 70 106 (Fig. 10) is joined to the duct 113 which goes to the top of the vertical cylinder 78 (Fig. 9). The passage 107 is connected to a duct 114 (Fig. 9) which joins the exhaust bore 29. An exhaust feeder 115 in the casting 14 (Fig. 9) communicates at one end with the duct 114 and at

its other end is coupled at 116 to an exhaust hose 117.

The passage 108 joins a duct 118 in the casting 14 (Fig. 9) which is coupled at 119 (Fig. 6) to the previously mentioned common pipe 80. It will be understood from Fig. 9 that the various 5 passages and feeders in the casting 14 are produced by boring the latter in the required directions. Some of the borings necessarily cross each other in order to properly loop the fluid, 10 the otherwise open ends of the passages being plugged to produce the required closures.

Tracing the continuations of the high pressure and exhaust hoses 111, 117 (Fig. 6) it is seen in Fig. 3 that these terminate at the stand pipes 15 such as 120, of a pair of pumps 122, 123 (Fig. 1). The first of these is the high pressure pump which takes its fluid supply from the sump 124 into which the bottom of the base 1 is converted. The second of these is the exhaust pump, the 20 discharge pipe 125 of which (Fig. 3) is directed into the sump. These pumps are driven in unison by a gear train 126 (Fig. 1), the train in turn being driven by a motor 127.

Mention has been made of a saddle casting. 25 This casting is now designated 128 (Figs. 1 and 6). This casting is slideable upon the heads 25, 26 (Fig. 4), toward which end the casting is recessed at 129 to embrace the heads. Those portions of the casting which come flush with the 30 backs of the heads have plates 130 which engage said backs and thus hold the casting to the heads. The saddle casting has a forwardly extended rib 131 (Figs. 15 and 16) along the top and a bracket extension 132 along the bottom. The forward 35 end of this extension is flanged at 133. The bracket 132 is braced at 134 because of the weight which is imposed upon it.

A hub 135 (Fig. 16) or back of the saddle casting 128 is bored at 136 to provide a seat for a 40 bottom thrust bearing 137. Said bore houses the sleeve 138 of what has been termed a nut 139. The sleeve and nut are kept in proper relationship to the bore 136 by a bracket 139a (Fig. 16) secured to the extension 132. This nut is peripherally formed into a worm gear 140, the bore 136 being counter-bored at 141 to make room for the shouldered portion of the gear and nut.

Said worm gear and nut have a threaded bore 142 (Fig. 16) in which the threaded portion 143 50 of the shaft 144 is screwed. This shaft, also herein known as the vertical lead screw, is equipped at its lower end with a plunger 145 (Fig. 6) which occupies the vertical cylinder 78. That portion of the casting 14 through which 55 the plunger shaft 144 necessarily passes, is equipped with a packing gland 146 (Fig. 2) to prevent the upward escape of pressure fluid.

The upper end of the screw and plunger shaft 144 (Fig. 1) has a cable 147 coupled to it. This 60 cable is directed over a sheave 148, and it carries the previously mentioned counter-weight 24 (Fig. 4). The sheave is journalled on a support 149 on top of the column 22. A worm pinion 150 (Figs. 6 and 17) meshes with the gear 140. This 65 pinion is carried by a counter-shaft 151 which is appropriately journalled beneath the bracket 132 and carries a spur gear 152 on its forward extremity. A pinion 153 meshes with this spur gear. The pinion is carried by a stub shaft 154 70 which is suitably journalled in a bearing 155 that is mounted by the saddle casting 128. Said shaft has an attached hand wheel 156 which when turned either causes a raising of the saddle casting 128 and all of its carried parts, or permits 75

the lowering of the latter. The hand wheel 156 is necessarily turned in one or the other direction to accomplish these diverse purposes.

The saddle casting 128 and its carried parts 5 are counter-balanced by the weight 24 with fair accuracy. The saddle casting, however, is not suspended directly from the end of the cable 141. The lead screw 143 and nut 139 (Fig. 16) constitute the intermediary connection. This arrangement has the important advantage of 10 perpetually imposing the dead weight of the saddle casting 128 and its carried parts upon the nut 139 so that there is never any back lash between the top of the thread 143 and the top of the 15 thread passage in the nut and sleeve.

In other words, the dead weight of the saddle casting and its carried parts is used to eliminate the back lash between the thread on the lead screw and the thread passage in the nut and sleeve which is the inevitable result of the 20 operation of the machine over an extended period, the so-called elimination occurring only to the extent to which it would be damaging to the operation of the cutter (Fig. 1).

Any obstruction in the course of the cutter point 25 inopportunely present in the work 10, would result in the cutter climbing the obstruction and raising the saddle casting 128 if the latter were directly counter-balanced by direct suspension from the cable 141. But by suspending 30 the lead screw 143 from the cable, thereby making the saddle casting and its carried parts indirectly dependent from the cable, said saddle casting and its parts are permitted to constantly 35 remain in the anti-back lash position, thereby backing the cutter up with a dead weight, the inertia of which supersedes by far any lifting effort that the cutter might ever tend to respond to because of encountering an obstruction in the 40 work, as aforesaid.

It is thus that the cutter is stabilized at any 45 particular cutting point which it might occupy. This stabilization is augmented by the dash-pot which the vertical cylinder 78 and its contained plunger 145 and liquid affords.

The bracket 132 (Fig. 15) provides the slide-way for a part which is hereinafter known as the 50 head casting 157 (Figs. 1, 6 and 7). This casting has a flange 158 which abuts the flange 133 (Fig. 3) and is overlaid with a plate 159 which holds 55 the base of the head casting 157 down. The top portion of said casting is grooved at 160 (Fig. 3) to contain the edge of a plate 161, which is secured to the rib 131. The plates 159, 161, guide the head casting 157 in its lateral movements.

Said casting is enlarged to comprise the previously described horizontal cylinder 69. The latter consists of a bore in the casting (Fig. 6), the right end being headed at 162, the left end 60 being closed by a flange 163, on which a stuffing box 164 is mounted. A piston 165 is situated in the cylinder 69. This piston and rod are carried by a bracket 166 which is affixed to the saddle casting 128 by bolts 167. The piston 165 thus 65 remains stationary. The admission and escape of fluid to and from the cylinder 69 at opposite sides of the piston causes the entire head casting 157 to slide either to the right or left in respect to the saddle casting 128.

The head casting 157 carries a quill 168. This 70 quill has a key 169 which occupies a keyway 170 in the head casting 157. The quill is rectilinearly adjustable with respect to the head casting 157 for which purpose it is toothed at 171 (Fig. 6) to 75 provide for the engagement of a turn-key 172

(Fig. 7). This key is turned with a wrench and the result is the foregoing adjustment of the quill. The latter is secured in its adjusted positions by a lock (Fig. 8) which consists of a pair of blocks 173. A bolt 174 is screwed into one of these 5 blocks and has its head in engagement with the other block. When the bolt is turned clockwise it draws the blocks 173 together and into locking contact with the wall of the quill 168. The latter is loosened by turning the bolt 174 in 10 the reverse direction.

It will be understood from Figs. 6, 7 and 8 that the quill 168 occupies part of a bore 175 in the head casting 157. The quill is adjustable in said bore, the extent of the toothed surface 171. A 15 spindle 176 is revolvable in the quill on sets of roller bearings 177. The right end of this quill carries a collet chuck 178 by which a cutting tool 179 of any desired description is gripped. The spindle is held in position in the quill 168 by 20 an appropriate arrangement 180.

Beyond this arrangement 180 the spindle 176 is fluted at 181 (Fig. 6) to contain the splines 182 of a bushing 183 of a multi-grooved pulley 184. This pulley is mounted on a ball bearing 185 25 which is supported by a bracket 186 attached to the saddle casting 128. As the quill 168 is adjusted to set the cutting tool 179 up to or away from the work, its fluted spindle slides in respect to the pulley 184 but without disturbing the driv- 30 ing connection of the latter.

A standard 187 (Figs. 1 and 6) provides the support for the tracer block 38 upon the head casting 157. The latter is grooved at 188 (Figs. 3 and 6) to contain the heads of the bolts and 35 nuts 189 which hold the standard down. This arrangement provides for a limited adjustment of the tracer assemblage 38 in respect to the head casting 157. The standard 187 carries a member 190 (Fig. 1) which is dove-tail grooved at 191 40 to contain a correspondingly shaped rib 192 on the bottom of the block 38. The block has limited adjustment in respect to the member 190, this being accomplished by a screw 193 which is mounted upon the member 190 and has threaded 45 engagement with the block 38.

Provision is made for locking the head casting 157 upon the saddle casting 128 so that the cutting tool 179 is prevented from wavering during horizontal and vertical milling. This provision 50 comprises a fairly heavy screw 194 (Figs. 1 and 4) which is rigidly affixed at 195 to the bracket 166. This screw is parallel to the axis of the horizontal cylinder 69. The latter has a lug 196 with which the screw 94 has unthreaded engagement. A pair of nuts 197, 198 is threaded 55 on the screw 194 and as one or the other of these is driven along the screw the entire head casting 157 is adjusted accordingly in respect to the saddle casting 128. These nuts are then locked 60 against the lug 196, thus securing the head casting 65.

Driving power for the cutting tool 179 is supplied by a motor 199 (Fig. 3). The shaft of this motor carries a multi-groove pulley 200 (Fig. 4) 65 which is belted to the pulley 184 at 201. The motor is mounted on a base 202 (Fig. 3) which is adjustable by a screw and crank 203 in respect to a shelf 204 which extends backward from the saddle casting 128.

Attention is now directed to the tracer 38 (Fig. 18). The sleeve 40 is internally threaded at 205 at one end to enable the screwing in of a valve cap 206. This cap has a thimble 207 screwed into it, the bottom of the thimble providing a rest 70 75

for one end of a spring 208 and having a hole 209 for the guidance of a rod 210. The use of this rod is optional, the only purpose in illustrating it being to disclose a plan whereby the valve 48 could be operated manually. If the latter provision is not desired then the rod 210 would be omitted.

The inner end of the rod 210 is screwed into the apex of a central cone 211 which arises from a web 212 across the piston valve 48. The inner end of the spring 208 abuts a portion adjacent to the cone 211. The spring 208 is necessary to tend to constantly urge the piston valve 48 in the direction of the master. This function of the spring also keeps the cone 211 in contact with the balls 218 in the conical portion 219 of a retainer 220.

The cylindrical part of the retainer 220 fits loosely inside of a tracer tube 221, the inner end 20 of said tube carrying a hardened race 222 upon which the balls 218 ride. A universal ball bearing 223 has a slip fit upon the tracer tube 221. This bearing is situated adjacently to a collar 224 on the tube, the latter being slightly spaced 25 from the bearing at 225 when the piston valve 48 is in the neutral position. The balls of said bearing ride upon a concavity 226 in the outer ring 227 of said bearing. Thus the tracer tube 221 is capable of universally rocking within slight 30 limits, and it is also capable of back and forth sliding movement in respect to the universal bearing 35 in.

A shell 228 is screwed onto the externally threaded end 229 of the sleeve 40. This shell supports the bearing 223 and consequently the tracer tube 221 and at the same time confines any leaking oil which may have escaped the concavity 52. The shell 228 has a cylindrical terminal 230 in which the outer ring 227 has a slip fit. This cylindrical terminal is threaded at 231 to receive an adjusting nut 232. This nut is adapted to set the piston valve 48 in proper relationship to the series of passages 42, 46, and to regulate the speed of travel of the tracer 38 and its train toward the 45 master.

An adapter 233 is secured to the forward end of the tracer tube 221. This adapter has a threaded stem 234. The purpose of the latter is to carry a tracer head 235. Tracer heads may be supplied in 50 various sizes in order to suit various types of work. Usually a tracer head is made of aluminum, fiber, or some other light material. Generally the tracer head is very slightly larger in diameter than the cutter 179 with which it cooperates.

The operation is readily understood. The machine is adapted to do three outstanding classes of work, first, to vertically traverse the contour of the upright surface of a master by means of the tracer head 235, thereby to simultaneously cause 55 an identical response of the cutter 179 with respect to the work 10, the successively fresh point cutting planes being produced by slight manual turns of the hand wheel 21. Second, to cause the tracer head 235 to perform perimetric tracing 60 wherein it is made to feel out the top and bottom edges of a master and accordingly regulate the position of the cutter 179 for side cutting into the top and bottom edges of the work 10, the up and down traverses of the tracer being under the automatic regulation of the vertical cylinder 78 and its plunger 145. Third, to lock the cutter 179 at 65 the desired distance from the saddle casting 128, then to cause the cutter to do straight vertical milling either by working the hand wheels 156 and 21 in conjunction with each other or working 70 75

the reversing valve 81 in conjunction with the hand wheel 21, or to cause the cutter to do straight horizontal milling by manipulating the hand wheels 156, 21 in conjunction with each other.

Before describing the details of the foregoing three phases of operation of the machine, it is desired to briefly set out the manner in which the machine is prepared for doing work. The master 8 and the work 10 are secured to the foundation 7 (Fig. 1). The master may comprise any kind of a pattern or model. It may have a front surface contour which it is desired to duplicate, or it may have top and bottom boundaries of special shapes which it is desired to reproduce in the work. When straight vertical or horizontal milling is done, there is no need for a pattern. The work 10, if not already roughed out into shape as it would be if it were an unfinished casting, will comprise a generally shapeless block of the material, out of which it is desired to reproduce the master 8.

For the purpose of the present illustration, the master 8 may be considered as comprising a horizontally elongated plaster cast, which in its cross sectional contour includes the vertical ogee curve. The longitudinal surface of this curve may be perfectly straight, or it may include eminences or depressions which the reader can readily visualize without the necessity of an illustration. The settings which can be accomplished by the adjusting nuts 189 (Fig. 6) and the screw 193 (Fig. 1) of the tracer assemblage are generally fixed in nature. That is to say, when settings are once made here they are not usually disturbed.

In making an original setting it is necessary to vertically align the front face of the tracer head 235 with the front face of the cutting tool 179 (Fig. 1). This is done by adjusting the quill 168 (Fig. 6). Cutters 179 are not always of the same 40 length and when there is any deviation from the foregoing vertical alignment it is necessary to unlock the quill at 173, 174 (Fig. 8) and to turn the key 172 (Fig. 7) until the desired alignment is obtained.

The description is now reverted to the previously mentioned three phases of operation, the first of which comprises the vertical surface contouring of the master 8. The assemblages of the tracer 38 and the cutter 179 (Fig. 1) move back 50 and forth in unison on horizontal lines. The head casting 157 must be free to slide back and forth in reference to the saddle casting 128, and this freedom of motion is permitted by adjusting the nuts 197, 198 far enough away from the lug 55 196.

Presumably the first cut will be started from the top of the work 10 at the end nearest the observer (Fig. 1). The saddle casting 128 and its carried parts are regarded as travelling downwardly in the direction of arrow a. The hand wheel 156 is initially turned to elevate the saddle casting 128 until the tracer head 235 and the cutter 179 are set at the top of the master and work. Thereafter the hand wheel 156 is turned slowly in the reverse direction to lower the assemblage (arrow a, Fig. 1) then turned in the other direction to again raise the assemblage, each of the latter acts being accompanied by a slight turn of the hand wheel 21 to reposition 70 the tracer head and cutter at the beginning of a fresh stroke.

Upon starting the motor 127 (Fig. 1) the high pressure and exhaust pumps 122, 123, respectively drive high pressure fluid through the hose 75

111 (Fig. 6) and tend to draw fluid from the exhaust hose 117. High pressure fluid is thus introduced into the central passage 44 (Fig. 20) by way of the coupling point 112 (Fig. 9), feeder 5 110, duct 109, high pressure bore 30, hose 33 and duct 55 (Fig. 19). The flow to exhaust is traced from the passage 42 and 46 (Fig. 20) through the by-pass 49, duct 54 (Fig. 19), hose 34, exhaust bore 29 (Fig. 9), duct 114, feeder 10 115, coupling point 116 and the previously mentioned hose 117.

Move the handle 73 to the horizontal position (Fig. 1). This places the valve plug 70 in the position shown in Fig. 18. The kerf 14 (Fig. 13) 15 connects the ports 61 and 63, the latter having the hose connection 65 to the left end of the cylinder 69. The kerf 75 connects the ports 62 and 64 so as to establish communication through the hose 66 with the right end of the cylinder 20 69.

Now turn the hand wheel 156 slowly (Fig. 1) so as to lower the saddle casting 128 (arrow a, Fig. 1). As the tracer head 235 rides down the incline of the master 8 the piston valve 48 is urged 25 to the right (arrow b, Fig. 18) because of the spring pressure behind it. The passage 44 (Fig. 20) is uncovered so that high pressure fluid enters the passage 43. It is conducted through the duct 56 and port 58 (Fig. 18) to the right end 30 of the cylinder 69. The pressure reaction against the stationary piston 165 drives the entire head casting 157 to the right (arrow c, Fig. 1). This drives the cutting tool 179 into the work to an extent equal to the advance of the 35 tracer head.

At the same time the fluid in the cylinder 69 40 at the left of the piston 175 is forced through the diagonal port 60 (Fig. 18) and the duct 57 to the passage 46 which is now uncovered by the closure 215, permitting the exhaust fluid to reach the hose 33 and pass onto the pump 123 (Fig. 1) by way of the bore 29 (Fig. 9) duct 114, and the previously described feeders 115.

When the tracer head 235 rides up an eminence instead of moving down grade, as just described, the reverse of the foregoing operation takes place. The piston valve 48 is then shifted to the left (arrow d, Fig. 18) to admit high pressure fluid to the passage 45. This is delivered 45 to the left end of the cylinder 69 by way of the duct 51, port 60 and hose 65. Exhaust fluid from the right end of the cylinder is conducted to the passage 42 by way of the ports 64 and 58 and the duct 56.

Circumstances might be such wherein it is not desired to produce the periodic raising and lowering of the saddle casting 128 by the continuous 55 manual operation of the hand wheel 156. This act can be done automatically by cutting in the reversing valve 81. The three-way valve 37 is not disturbed; its handle 13 remains in the horizontal position (Fig. 1). The ensuing operation of the machine is still semi-automatic because of the necessity for the operator's presence for the turning of the hand wheel 21 to advance the tracer and cutter assemblages into successively 60 fresh stroking planes.

Up to this moment the reversing valve 81 has been locked in the neutral position. This position is signified by the upright position of the lever 91 (Fig. 11). The actual neutralization of the reversing valve comprises locking the plug 65 70 (Fig. 12) centrally across the ports 100, 102 (Fig. 10), this being accomplished when the 75 point of the thumb screw 92a is nested in the

depression 93a (Fig. 22) of the fixedly carried washer 87.

It is quite possible that the lever 91 (Fig. 11) will not remain in the erect position illustrated, and if it should fall to one side of the other it 5 will simply be stopped by the engagement of one end of the slot 93 with the pin 29. The latter comprises a rigid abutment because of its being a part of the now locked plug 86. So in order to 10 cut in the reversing valve 81 the first act is to back off the thumb screw 92a. This frees the plug 86 and it is necessary for the operator to see to it that the lever 91 is caused to take the correct right or left position as is necessary to 15 produce the next up or down stroke of the saddle 20 casting 128. For example, if the saddle casting 128 should have stopped at the top of its stroke, the lever 91 will be switched over to the right, as shown in Fig. 1. This act turns the plug 86 so that the kerf 103 stands in the relationship to the 25 ports 99, 100 shown in Fig. 10. These ports are now open and high pressure fluid is delivered to the top of the cylinder 78 (Figs. 1 and 6) by way of passages 105, 106 (Fig. 10). This drives the plunger 145 downwards in the vertical cylinder, 30 carrying the saddle casting 128 and its carried parts downward (arrow a, Fig. 1).

When the guide 86 (Fig. 1) reaches the stop 98 a reversal of the valve 81 occurs. The weighted lever 91 is turned counter-clockwise slightly past 30 dead center. The lever 91 then topples over, moving the plug 86 from the full to the dotted line position (Fig. 10). The port 100 is now closed from the high pressure port 99 and the port 102 is opened. High pressure fluid is now 35 delivered to the vertical cylinder 78 by way of the passage 108 (Fig. 10). The plunger 145 is driven upwards (Fig. 1), the saddle casting 128 and its carried parts going with it.

The second phase of operation of the machine 40 comprises what has been conveniently termed perimetric tracing. This involves a master 8 which has top and bottom edges desired to be reproduced in the work 10. The term "edges" is used in a broad sense. They can comprise special shapes along top and bottom margins of the master, lying substantially parallel to each other or diverging from the parallel relationship until they comprise virtually half circles. The sense 45 which it is desired to impart by these statements is that in the second phase of operation the tracer head 235 makes contact either with the top or bottom margins of the master at its sides, as distinguished from the tip contact in front surface contouring. On the same principle the side of 50 the cutter 179 is employed to remove material from the top or bottom of the work 10 as distinguished from the routing operation accomplished by the tip contact of the cutter with the work in vertical surface contouring. 55

The first acts are to neutralize the reversing valve 81 (Fig. 10) and to reverse the position of the three way valve 37 (Fig. 18). The reversing valve 81 is neutralized by turning the screw 92a inward (Fig. 12) until its point is again 60 nested in the depression 93a (Fig. 2). The plug 86 is now to be regarded as closing off the two ports 100, 102. The reversal of the three-way valve is accomplished by turning the handle 13 65 (Fig. 18) 90 degrees in the downward direction 70 so that the kerfs 14, 75 stand in the dotted line position.

Another necessary act comprises the locking of the head casting 157 (Fig. 1). This is done 75 by turning the nuts 197, 198 toward each other

on the screw 194 until they bind against the lug 196.

It is assumed that the bottom boundary of the master is to be traversed first. This may, and for illustration is, regarded as having an up and down contour. This contour is traversed by turning the hand wheel 21 in the proper direction from the desired starting position. The reason for selecting the bottom boundary for the initial traversal is that the tracer 38 automatically causes the elevation of the saddle casting 128 when left free to do as it will, so to speak.

This function is readily understood by referring to Fig. 18. The operator is presumed to have maneuvered the saddle casting 128 until the tracer head 235 stands clear of the master 8 below the bottom margin. The unrestricted tendency of the spring 208 is to move the tracer tube 221 to the right (arrow b, Fig. 18).

The piston valve 48 thus establishes high pressure fluid communication between the passages 44 and 43. High pressure fluid is therefore delivered to the hose 36 by way of the ducts 56 (Fig. 18) port 58, kerf 75 and port 62.

From the hose 36 the passage of the high pressure fluid is traced to the bore 32 (Fig. 1), duct 77, coupling point 119 and pipe 80 to the bottom of the vertical cylinder 78. The upward pressure on the plunger 145 (arrow e, Fig. 6) elevates the saddle casting 128 as previously explained, causing the side of the tracer head 235 to contact the bottom margin of the master 8.

The upward travel of the saddle casting 128 is stopped automatically by the tracer. Since the head 235 is now in contact with the bottom margin of the master, the elevating motion of the casting 128 causes the tracer tube 221 to turn clockwise on its universal bearing 223. The result is a backward push on the piston valve 48 (arrow d, Fig. 18). The passages 44, 45, are thus made to communicate. High pressure fluid is delivered to the hose 35 (Fig. 4) by way of the duct 57 (Fig. 18) diagonal port 60 (Fig. 13) and kerf 74. From the hose 35 said fluid is delivered to the top of the cylinder 78 (Fig. 9) by way of the bore 31 and duct 76; the resulting downward pressure on the plunger 145 (arrow f, Fig. 6) will lower the saddle casting 128.

Now the operator must stand ready to turn the hand wheel 21 (Fig. 1) in the proper direction to advance the column casting 14 and all of its carried parts along the base 2. As the side of the tracer head 235 encounters high and low places it will affect the piston valve 48 (Fig. 18) in either one or the other two ways described, thus either lowering or raising the saddle casting 128, keeping the tracer head in contact with the bottom margin of the master 8 and causing the side of the cutter 179 to reproduce the precise contour along the bottom margin of the work 10.

The next step in the foregoing phase of perimetric tracing comprises elevating the saddle casting 128 sufficiently high to dispose the tracer head 235 and the cutter 179 (Fig. 1) above the top margins of the master 8 and work 10. This is accomplished by merely permitting the tracer head 235 to go free. It will be remembered that the natural tendency of the spring 208 is to urge the tracer tube 221 to the right, the consequent displacement of the piston valve 48 directing high pressure fluid to the bottom of the vertical cylinder 78 and causing the elevation mentioned of the saddle casting 128. In order that this act may be performed it is obviously necessary

that there shall not be any obstruction on the side vertical face of either the master 8 or work 10, and if there is such an obstruction, it is necessary to temporarily shift the head casting 157 to the left. This can be done either by backing off the nut 197 and turning the nut 198 against the lug 196 until the head casting 157 has been displaced to the left the desired distance, or the three-way valve can be momentarily restored to the full line position in Fig. 18, thus to displace the head casting 157 by the power of pressure fluid. To this end it is also necessary to back off the nut 197. The operator will either press on the tracer head 235 to the left or pull it to the left by means of the rod 210 (Fig. 18) whereupon a delivery of pressure fluid into the cylinder 69 (Fig. 6) on the left side of the piston 165 will accomplish the stated purpose.

The latter having been achieved, it is necessary to again move the handle 73 down. This relocates the three-way valve 37 into the dotted line position in Fig. 18. Now it is necessary to turn the auxiliary reversing valve plug 38a (Fig. 23) into the position of Fig. 25 by moving the handle 40a from the full to the dotted line position in Fig. 24. The tracer head 235 being unrestrained is again moved to the right by the spring 208. The passages 44, 43 (Fig. 18) are again placed in communication. Pressure fluid is delivered to the duct 56, port 58 and port 62, whence it enters the hose 36.

From there the pressure fluid is delivered to the bore 31 by way of the spiral passage 46a (Fig. 25). The bore 31 delivers the pressure fluid to the top of the cylinder 78 (Fig. 9) by way of the duct 76. The resulting downward pressure on the plunger 145 (arrow f, Fig. 6) lowers the saddle casting 128 (Fig. 1) and consequently engages the sides of the tracer head 235 and cutter 179 with the top margins of the master 8 and work 10.

At this point is readily seen that were it not for the auxiliary reversing valve 37a the high pressure fluid delivered to the hose 36 would enter the bore 32 and eventually reach the bottom of the cylinder 78. The resulting raising of the plunger 145 would raise the tracer head and cutter from the top margins of the master and work, and this would be contrary to what is necessary under the instant circumstance.

Having lowered the saddle casting 128 until the foregoing contacts of the tracer head and cutter are established with the top margins of the master and work, the ensuing operation is but a repetition of what has already been described during the contouring of the bottom margin of the master. The operator turns the hand wheel 21 so as to traverse the master and work with the tracer head and cutter, the tracer responding to the undulations in the top margin of the master and causing a faithful reproduction in the top margins of the work by the resulting control of the cutter.

The third phase of operation of the machine comprises straight milling. This can be done with the absolute assurance that there will be no wavering in the line of cut, whether the milling is vertical or horizontal. Moreover the conversion of the apparatus into a milling machine from a contouring and duplicating apparatus, or reconverting the apparatus from a contouring and duplicating machine into a milling machine, does not affect the accuracy of the mechanism in the least. In other words, the apparatus can be run as a duplicating machine for any desired

period and then converted into a milling machine for a run of any further desired period. On the same principle the machine can be changed back and it will function perfectly without any loss of quality.

It is first necessary to restore the auxiliary reversing valve 31a to its normal position (Fig. 23). The three-way valve is ordinarily used to displace the head casting 157 so far to the right as desired. The adjustment of the three-way valve is then to the full line position (Fig. 18) the handle 74 (Fig. 1) standing horizontally. The natural tendency of the spring 208 to shift the tracer head 235 to the right results in the admission of pressure fluid, by the displacement of the piston valve 48 (arrow b, Fig. 18), to the right end of the horizontal cylinder 69. The front end of the cylinder 69 is filled to the limit. The fluid between the front of the piston 165 (Fig. 6) and the head 162 of the cylinder constitutes an incompressible abutment.

If the point of the cutter 179 is then not in proper contact with the work 10, any necessary adjustment is made by means of the nuts 191, 198 and the lug 196. At this time it is required that the tracer head 235 shall be back out of the way because the tracer does not function either in horizontal or vertical milling. The tracer assemblage is thus displaced by loosening the bolts and nuts 189 (Fig. 6) and sliding the tracer standard 187 back upon the top of the cylinder 168.

The machine is now ready to do either horizontal or vertical milling. If the horizontal milling is done first, the successive cuts are started by turning the hand wheel 156 so as to lower or raise the saddle casting 128 a little at a time, depending on whether the operation is begun at the bottom or top of the work 10. The cutter 179 is carried along the cut by turning the hand wheel 21.

Vertical milling can be accomplished by working the hand wheels 156 and 21 together. The hand wheel 156 is used to produce the vertical cuts and the hand wheel 21 is used to advance the cutter 179 to the beginning of each new cut.

But in vertical milling, the work can be materially lessened by using the reversing valve 81 for elevating and lowering the saddle casting 128. This relieves the operator of the necessity of turning the hand wheel 156 so that he has only the hand wheel 21 to look after. The weighted lever 91 is loosened by means of the thumb screw 92a (Fig. 12) and is made to fall in one or the other of the two directions so as to shift the plug 86 (Fig. 10) either into the full or dotted line position.

If the cutter 179 happens to be at the top of the cut, the lever 91 is made to fall to the right (Fig. 1). This places the valve plug 86 (Fig. 10) in the full line position. Pressure fluid delivered from the high pressure bore 30 (Fig. 9) by way of the duct 109 enters the passage 105 (Fig. 10) and reaches the top of cylinder 78 by way of the passage 106 (Fig. 10) and duct 113 (Fig. 9). The resulting down pressure on the plunger 145 lowers the saddle casting 128 so as to carry the cutter 179 on its down cut.

When the latter is completed the reversal of the valve plug 86 to the dotted line position (Fig. 10) shunts the high pressure fluid to the bottom of cylinder 78 by way of the passage 108 (Fig. 10), duct 118 (Fig. 9) and pipe 80. The upward pressure on the plunger 145 raises the saddle casting 128.

It is desired to lay emphasis on the function

of the saddle casting 128 and its carried parts as the stabilizing factor of the cutter 179 in the foregoing milling operations, especially straight horizontal milling. The reader can readily understand that if the cutter 179 were not held down to its work it would be possible for said cutter to make what is conveniently called a climb cut when a high place is encountered by the cutter. The inertia of the saddle casting 128 and its carried parts is far superior to the power available at the point of the cutter 179 to make the foregoing climb cut. In other words, the saddle casting 128 and its carried parts represents a mass having a weight sufficient to hold the point of the cutter 179 to the line of cut, thereby preventing any deviation whatsoever of said point. This facility is attributed directly to the fact that the saddle casting 128 is hung upon the nut 139 (Fig. 16) and thus indirectly attached to the cable 147 instead of being suspended from the cable directly.

The tracer 38 (Fig. 18) is thought to require an additional explanation, mainly to make the purpose of the universal bearing 223 and the space 225 clear. To begin with, the bearing 223 allows not only the sliding of the tracer tube 221, but the oscillation of it in any radial direction. The sliding function is accomplished by the sliding fit of the tube in the inner race. The oscillating function is accomplished by the riding of the balls upon the concavity 26 of the outer ring or race 227. The center of this concavity coincides with the axial center of the tube 221. Thus it is readily seen that the balls travel in a partially circular path which is centered on the axis of the tube.

The amount of the space 225 is regulated by turning the adjusting nut 232 either in or out. In beginning an adjustment the nut 232 is first turned clockwise. The nut is thus screwed into the thread 231. Inasmuch as the outer race 221 is in contact with the adjusting nut the universal bearing 223 is driven inwardly of the cylindrical terminal 230 to the left. The inner race of the universal bearing soon engages the collar 224. Thereafter the adjustment will be carried out until the piston valve 48 is centered over the high pressure (44) and exhaust (42, 46) passages. This constitutes a neutral or inactive position of the piston valve and tracer.

With this as a starting point the adjusting nut 232 is backed off. The spring 208 will cause the tube 221 to follow. The collar 224 remains in contact with the universal bearing. The extent to which the nut 232 is adjusted outwardly of the shell 228 later determines the amount of space that will occur at 225 when the tracer head 235 is brought into contact with this phase of the master.

On the same principle the amount of outward adjustment of the nut 232 and of potential space at 225 determines the speed of travel of the tracer head 235 toward the master in the event that the tracer head drops into an abrupt depression.

When the previously mentioned universal movement of the tracer tube 221 occurs, the piston valve 48 is shifted inward (arrow d, Fig. 18) because of the cam action of the balls 218 upon the cone 211. These elements are kept in perpetual contact by the spring 208 and the latter is depressed when the tracer tube 221 is oscillated, as described.

I claim:

1. A machine of the character described comprising a foundation for supporting a master and

- a piece of work, a cutter for operating upon the work, a tracer assemblage having a tracer head for traversing the master, pressure fluid operable means carrying the cutter, means correlated with the tracer assemblage making said carrying means responsive to the master in movements in one plane when the end of the tracer head traverses the upright surface contour of the master and when the cutter is in point contact with the upright surface of the work, and other means rendered responsive to said tracer assemblage by its correlated means in movements in a diverse plane when the side of the tracer head traverses at least one of the margins of the master and when the cutter is in side contact with a corresponding margin of the work and a settable selector valve for determining the reactive effect of the cutter as respects the end and lateral engagements of the master by the tracer.
20. 2. A machine of the character described comprising a foundation for supporting a master and a piece of work, a cutter for operating upon the work, a tracer assemblage having a tracer head for traversing the master, pressure fluid operable means carrying the cutter, means correlated with the tracer assemblage making said carrying means to reciprocate in one plane in response to corresponding reciprocations of the tracer head when said head is in end contact with the upright surface of the master for traversing the surface contour thereof and when the cutter is in point contact with the upright surface of the work, and other means rendered responsive by the correlated means of the tracer assemblage to the oscillations of the tracer head thereby to move the carrying means in a diverse plane when said head is in side contact with at least one of the margins of the master for traversing the contour thereof and when the cutter is in side contact with the corresponding margin of the work and a selector valve settable to determine the response resultant from endwise movement or lateral deflection of the tracer head.
3. A machine of the character described comprising a foundation for supporting a piece of work and a master having upright surface and marginal contours, a cutter for operating upon the upright surface and at least one margin of the work, a tracer assemblage having a tracer head for traversing the upright surface and at least one margin of the master, carrying means supporting the tracer assemblage and cutter in coupled relationship, said carrying means being variably stationed with respect to the foundation to maintain the cutter and tracer head either in point or side contact with the respective upright surfaces and margins of the master and work, and a selector valve positionable in agreement with the respective stations of the carrying means for selectively producing either horizontal or vertical reciprocations of the tracer head when coating with the respective upright and marginal surfaces of the master.
4. A machine of the character described for supporting a piece of work and a master having upright surface and marginal contours, a cutter for operating upon the work, a tracer assemblage having a tracer head for traversing the master, carrying means supporting the cutter and tracer assemblage in coupled relationship, manual means by which to station the carrying means in respect to the foundation for either a point or side contact of the cutter and tracer with the upright or marginal surfaces of the respective work and master, a pair of fluid pressure responsive elements respectively dedicated to reciprocating the cutter in one plane in response to reciprocations of the tracer head superinduced by the upright surface contour of the master, or to reciprocating the cutter in a different plane in response to oscillations of the tracer head superinduced by its traversing the margin of the master, a source of pressure fluid variably coupleable with said fluid responsive elements by way of the tracer for determining the positive and negative reactions thereof, and a settable selector device determining the controlling coupling of one or the other of said elements with the tracer.
5. A reproducing machine adapted either to upright surface or perimetric contouring, comprising a tracer assemblage including a tracer head and a cutter in coupled relationship, a common mount for the couple, means by which to set the mount either for point or side contact of the tracer head and cutter against the upright surfaces or margins of a master and a piece of work, a universal bearing for the tracer head allowing it to function either by reciprocation or arcuate oscillation thereof, a pressure fluid controlling valve responsive to either function of the tracer head, fluid pressure operated means producing axial reciprocation of the cutter when the couple is in upright surface work, fluid pressure operated means producing reciprocation of the cutter at right angles to its axis when the couple is in perimetric work, a pressure fluid system embracing both fluid pressure operated means and said controlling valve, and a manual valve in said system for shunting the functions of the controlling valve to either of said means as determined by the setting of said mount.
6. A convertible duplicating and milling machine comprising a cutter, a tracer assemblage including a tracer head, a movable mount supporting the cutter and tracer assemblage in coupled relationship, a pressure fluid system including a valve embodied in the tracer assemblage, a movable carrier on the mount for the cutter responsive to the valve when the tracer head is made to follow the variable contours of a master by the movements of the mount, means for displacing the tracer assemblage to set the tracer head away from the master, and means for then locking the erstwhile movable carrier to the mount so that the movements of the mount produce straight line cuts of the cutter, said means including an abutment carried by one of the parts, a screw secured to the other of said parts and slidably within the abutment, and clamp nuts adjustably mounted on the screw for movement in a desired clamping engagement with the abutment to lock the screw against translation with respect thereto.
7. A machine of the character described comprising a revoluble cutter, means for supporting the cutter in cutting relationship to the work, said means including a mount, counter-balancing means for the mount including a lead screw, and a nut journaled on the mount being in threaded engagement with the lead screw for adjusting the mount in reference to the lead screw, said nut providing the indirect suspension of the mount from the counter-balancing means and enabling the utilization of the dead weight of the mount to stabilize the cutter at its cutting point.
8. A machine of the character described comprising a revoluble cutter, means for supporting the cutter in cutting relationship to its work, said means including a saddle casting and an independently movable head casting which carries

the cutter, means for vibrating the head casting so as to move the cutter into and out of the work, counter-balancing means including a pendent lead screw, and a nut journalled on the saddle casting, being in threaded engagement with the lead screw to indirectly suspend the supporting means from the counter-balancing means, and utilize the dead weight of said supporting means in stabilizing the point of the cutter regardless of its in and out movements.

9. A machine of the character described comprising a revoluble cutter, supporting means for supporting the cutter in cutting relationship to its work, said supporting means including a saddle casting, counter-balancing means for the saddle casting including a cable having a weight and a lead screw pendent from its respective ends, a sheave supporting the bight of the cable, and a nut journalled on the saddle casting being in threaded engagement with the lead screw for suspending the saddle casting indirectly.

10. In a machine of the character described, a revoluble cutter, a head casting carrying the cutter, and including a cylinder, a saddle casting by which the head casting is slidably supported, a piston in the cylinder having means by which it is affixed to the saddle casting, means adapted to deliver pressure fluid into either end of the cylinder thereby to reciprocate the head casting, and means with which to lock the head casting when it is desired to prevent reciprocations, said means including a lug on the head casting, a screw affixed to the saddle casting and loosely occupying a hole in the lug, and nuts on the screw at each side of the lug, being adapted to be driven into jamming relationship with the lug.

11. In a machine of the character described, a revoluble cutter, a fluted spindle to which the cutter is coupled, a quill in which the spindle is revoluble, a saddle casting, cutter driving means carried by the saddle casting having splined engagement with the flutes of the spindle, a head casting slidably carried by the saddle casting, said head casting having a bore containing a portion of the quill, means providing a non-turning but slidable engagement of the quill with the bore, and means for adjusting the quill in the bore so as to set the cutter at various distances from the head casting without affecting the slidable function of the latter.

12. In a machine of the character described, a revoluble cutter, supporting means by which the cutter is carried, pressure fluid operable means for raising and lowering the supporting means, comprising a cylinder having a plunger and shaft, and means connecting the supporting means to the shaft and being adjustable in reference to the shaft thus to set the cutter in respect to its work independently of said raising and lowering means.

13. In a machine of the character described, a revoluble cutter, supporting means by which the cutter is carried, pressure fluid operable means for raising and lowering the supporting means, comprising a cylinder having a plunger and a screw shaft, and a nut journalled upon the supporting means, being in threaded engagement with the screw shaft and being turnable to raise and lower said supporting means upon the screw shaft and to set the cutter in respect to its work independently of the raising and lowering means.

14. In a machine of the character described, a revoluble cutter, supporting means carrying the cutter, a base movably carrying the supporting means, pressure fluid operable means carried by the base and coupled to the supporting means for

raising and lowering the supporting means, means for adjusting the supporting means in respect to the base independently of said fluid operable means, and means for moving the base in a plane different from that in which the supporting means is raised and lowered.

15. In a machine of the character described, a base structure, a revoluble cutter, a tracer assemblage including a tracer head, common supporting means by which the cutter and tracer head are carried in coupled relationship, a foundation upon which to attach a master and a piece of work for the purposes of the tracer head and cutter, and a bed casting having a top guide portion and a master and work support, both in upstanding relationship to the base structure, said bed structure having an upstanding peripheral flange defining a recess below the guide and support to receive cuttings from the work.

16. In a machine of the character described, a cutter, a saddle casting carrying said cutter, pressure fluid responsive means for reciprocating the saddle casting so as to cause the cutter to traverse a piece of work, a pressure fluid system in which said responsive means is connected, a base casting having means on which the saddle casting is guided and upon which the responsive means is supported, a reversing valve mounted on the base casting, the latter having ducts embodied therein coupling the pressure fluid system to the responsive means and to the valve, a ported plug embodied in said valve for shunting the fluid flow into the alternate ends of said responsive device, and means loosely connecting the saddle casting to said valve plug for producing automatic reversals of said plug as the saddle casting reciprocates.

17. In a machine of the character described, a tracer assemblage including a universally movable tracer head and a valve responsive thereto, and a cutter, fluid pressure responsive means under control of said valve upon which said assemblage and cutter are mounted in coupled relationship to either make point or side contact with the upright surface or margin of a master and a piece of work, a second pressure fluid responsive means for reciprocating the first-named responsive means in a plane at right angles to the axis of the cutter, a pressure fluid system in which both means are connected, said system including a manually operable valve which is set to cause the operation of the first-named responsive means, a reversing valve automatically actuated as said first-named means moves in its diverse plane, thereby to control the second pressure responsive means for causing the movements of said first named means in said diverse plane, means for shifting the first named responsive means so that the tracer head and cutter engage margins of the master and work, means for then neutralizing the reversing valve so that its function is suspended in respect to the second named responsive means, and means for shifting the position of the manual valve, transferring the function of the tracer head control valve from the first responsive means to the second responsive means.

18. In a machine of the character described, a tracer assemblage and a cutter in coupled relationship, a piston valve included in said assemblage having a spring tending to move it in one direction, a head casting by which the couple is carried, pressure responsive means for actuating the head casting, a pressure fluid system in which the valve and said responsive means are con-

- nected, supplying pressure fluid to one end of the responsive means for moving the head casting in one direction while the piston valve remains displaced by the pressure on the spring, and a reversing valve connected in said system, being turnable to shunt the influx of pressure fluid into the other end of said responsive means for moving the head casting in the opposite direction while said piston valve remains displaced by the spring behind it.
19. In a duplicating machine, a tracer head and cutter couple for traversing the upright surfaces respectively of a contoured master and of a piece of work, a saddle casting, a pair of pressure responsive means connected to the saddle casting, one of said means being movable in one direction in reference to the saddle casting and carrying the tracer head and cutter couple, the other one of said means causing the movement of the saddle casting in a different direction, a pressure fluid system, a valve embodied in said assemblage for controlling the fluid in said system, said valve including a tracer head-controlled cylinder, a high fluid pressure passage and adjacent passages communicating with the respective pair of pressure responsive means, and a manual valve also in said system to shunt the pressure fluid to either responsive means, so that the vibrations of the valve cylinder will cause reciprocal action either of the saddle casting or of said one responsive means.
20. A hydraulic control system for a duplicating machine of the type including a support for the work and master, a support for the cutter and tracer, a pair of slides intervening said supports for effecting their adjustment in two angularly related directions and pressure responsive devices for effecting movement of the slides, said system including a source of hydraulic pressure fluid, a valve for controlling the flow of fluid to the pressure responsive devices, a tracer directly reacting on said valve for varying the hydraulic reaction thereof, and additional valve means for determining the coupling of the pressure fluid to one of said pressure responsive devices by way of or exclusive of the tracer actuated valve.
21. A hydraulic control system for a duplicating machine of the type including a support for the work and master, a support for the cutter and tracer, a pair of slides intervening said supports for effecting their adjustment in two angularly related directions and pressure responsive devices for effecting movement of the slides, said system including a source of hydraulic pressure fluid, a valve for controlling the flow of fluid to the pressure responsive devices, a tracer directly reacting on said valve for varying the hydraulic reaction thereof, additional valve means for determining the coupling of the pressure fluid to one of said pressure responsive de-
- vices by way of or exclusive of the tracer actuated valve, and additional valve means for determining the directional effectiveness of the tracer controlled pressure fluid supply as respects said pressure responsive device.
22. A hydraulic control system for a duplicating machine of the type including a support for the work and master, a support for the cutter and tracer, a pair of slides intervening said supports for effecting their adjustment in two angularly related directions and pressure responsive devices for effecting movement of the slides, said system including a source of hydraulic pressure fluid, conduits coupled with the pressure responsive devices and variably connectible with the source of pressure fluid, and a series of control valves for determination of variable couplings of the fluid to the devices including a reversing valve normally biased for one direction of fluid coupling, a tracer stylus mounted for reaction on the valve to effect reversal thereof, and a selector valve in series with said biased valve and settable effectively to couple the latter with one or the other of said pressure responsive devices.
23. A hydraulic control system for a duplicating machine as in claim 21 wherein an additional serially disposed valve is employed to reverse the effect of the bias of the stylus actuated valve as respects the coupled pressure responsive device.
24. A hydraulic control system as in claim 21 wherein an additional valve mechanism is provided for coupling the pressure fluid to a pressure responsive device exclusive of said stylus actuated valve.
25. In a hydraulic duplicating machine control system of the character described, the combination with a hydraulically responsive device for effecting reciprocations of a cutter, the combination with conduits coupled with said device, of a first pump having its output coupled to said conduits to produce actuating pressure therein, a second pump having its intake coupled to said conduits, a reversing valve shiftable variably to determine the couplings of the respective pumps with the pressure responsive device conduits, and a pattern engaging stylus mounted for reaction on said reversing valve automatically to control the positionings thereof and thus the operative path followed by the cutter.
26. A structure as in claim 25 in which the reversing valve is biased to effect a selected coupling of the first pump with the pressure responsive device for actuation thereof in a given direction and additional valve means are provided for disconnecting the first pump and connecting the second pump with the pressure responsive means during said biased position of the stylus actuatable reversing valve.

EDMUND LEO WALL.
